SIGNALING SYSTEM FOR TELEGRAPH
LINKS

Roelof M. M. Oberman, The Hague, Netherlands

Application July 30, 1947, Serial No. 767,521
In the Netherlands April 24, 1944Section 1, Public Law 690, August 8, 1946
Patent expires April 24, 1964

5 Claims. (Cl. 178—69)

1

The invention refers to signalling in a telegraph system which preferably uses teleprinters operating on a start-stop code; the usual five unit code may be used which comprises a starting element (mark), five units which may be either mark or space, and a stop element (space), which code when suitably permutating the possible variations gives $2^5=32$ different signals. The teleprinter reacts to 31 of these 32 signals, but not to the one consisting of five marks (if no-current is mark and current space). The purpose of the invention is to effect special signals on a connection e. g. for closing a connection or for operating a particular device in the connection as for instance a monitoring set or a time indicator under the control of this thirty-second telegraph signal.

Operating particular signalings in telegraph systems by using slowly releasing relays supervising the position of the polar relay armatures is known. It is impossible however due to the considerable divergence in the release times of such relays, when using them for particular signals to prevent the printing of undesired signals.

It has been possible to entirely prevent the printing of undesired signals by means of special interruptors and other structural features in the teleprinters (El. Communication, v. 17, p. 375).

The purpose of the invention is the provision of a signalling system in which particular signals can be sent while using ordinary teleprinters without undesired signals being printed.

The system of the invention uses to this effect a supervisory device on the transmission relay armatures which can only operate on telegraph signals all of which have equal signalling elements, e. g. mark.

The key set of the printers should be provided with a key which emits, when operated, the signalling combination consisting in the usual five-unit code of a starting element (mark), five marking signal elements and a stop element (space). This is therefore a normal signal on which the printers start, but do not print. The system of the invention presents the advantage that the printing of undesired signals is prevented during the transmission of the special signal without requiring any special constructions in the teleprinter.

2

The invention will be described with reference to some figures showing an embodiment which is shown as far as is required for illustrating the invention.

5 Fig. 1 shows the principle of the signalling circuit;

Fig. 2 shows the principle of Fig. 1 with a tube added;

Fig. 3 is the circuit of Fig. 1 with a cold cathode 10 gas tube;

Fig. 4 shows a variation of Fig. 2.

The armature *a* of a polar receiving relay *A* is supervised in Fig. 1 by the relay *LA*. The relay *A* being commutated by the line alternations connects its tongue alternatively to — and + telegraph battery. Tongue *a* receives 32 signals in the manner described, every signal being preceded by a start element and followed by a stop element, the teleprinter reacting to 31 of the 32 signals, but not to the thirty-second. The circuit of the invention reacts to this thirty second signal and by sending it a response may be obtained at the receiver resulting e. g. in the control of any desired function. This armature *a* is coupled to the charging circuit of a condenser *C1*. The latter is connected through a resistive element such as a resistance *W1* to the armature *a*, the other condenser pole being connected to a battery pole. Armature *a* short-circuits the condenser circuit in spacing position so that it is discharged.

Energising the polar relay *A* by telegraph signals causes the armature *a* to change-over in a certain rhythm to the other battery pole. Condenser *C1* is thus charged and discharged in the same rhythm, the time taken by the charging and discharging of the condenser *C1* being dependent on the resistance value of the resistive element *W1*. The blocking cell or diode *S1* is connected across the resistance *W1*, in such a way that it is not conducting while armature *a* is in contact with the front contact and is conducting while armature *a* is in spacing position. In conducting condition cell *S1* has such a low resistance that the condenser *C1* is completely discharged when armature *a* is in spacing position for the time of one signal element, i. e. during 20 milliseconds for normal five unit code with a speed of 50 Baud. In this manner the discharged condition of condenser *C1* at the com-

mencement of each signal, i. e. after the space-stop-element of the preceding signal is ensured so that the result of the examination of the element of the coming signal is wholly based on those elements.

In the usual five-unit code, the signal having five consecutive marking elements as signal elements is not used as otherwise the printer would always print this signal after any line interruptions and the like.

This signal is particularly suited to the transmission of special signals, for it is not printed after its transmission; a print would be effected for any other signal in those systems using a lengthy line interruption for signalling purposes.

While armature a is in contact with the marking contact (—) condenser $C1$ of Fig. 1 receives continuous charging current, i. e. as long as marking current is transmitted. Cell $S2$ connected to the junction of condenser $C1$ and charging resistance $W1$ becomes conducting when condenser $C1$ is charged to half battery voltage. Relay LA then operates, actuating the signalling system.

The charging time of condenser $C1$, e. g. the time that passes between the attraction of armature a and the becoming conductive of cell $S2$, should be regulated for signals in usual five unit code and a speed of 50 Bauds to 100 milliseconds. Then the signal having the greatest similarity to the special signal (—+—+) cannot operate relay LA . In this manner LA operates during the last 20 milliseconds marking current of the special signal.

The circuit of Fig. 1 has the disadvantage that, when using a neutral relay, for relay LA , a condenser $C1$ of considerable size is required. This drawback is overcome by the circuit of Fig. 2 using a vacuum or a gas discharge tube $B1$. The grid of this tube is connected through a protecting resistance $W2$ to the junction of charging resistance $W1$ and condenser $C1$. The cathode of tube $B1$ is connected to ground or to a potentiometer. In spacing position of armature a the grid of this tube thus has a high negative voltage with regard to the cathode.

It is remarked that according to the C. C. I. T. (Comité Consultative Internationale sur la Télégraphique) the armature of a polar telegraph relay should be connected to + battery pole in spacing position. The opposite is the case if tubes are used as in the circuit of Fig. 2. With the aid of an auxiliary relay the circuit of Fig. 2 may be made to agree to existing systems.

The charge on condenser $C1$ is limited to half battery voltage in the circuit of Fig. 2 by providing cell $S2$. Tube $B1$ which preferably only becomes conducting when the grid voltage is slightly negative cannot get positive grid voltages because of the provision of cell $S2$. This cell, however, may be omitted.

Signalling relay LA attracts when tube $B1$ becomes conductive, whereby the special signal can now be received.

The anode voltage of tube $B1$ may be derived from the positive half of telegraph battery.

Fig. 3 shows the signalling circuit when a cold cathode gas filled tube is used. The anode of this tube $B2$ is connected through signalling relay LA to the positive pole of telegraph battery. The cathode is connected to the negative pole of the telegraph battery. The grid of this tube is connected through protecting resistance $W2$ to the junction of resistance $W1$ and condenser

$C1$. Condenser $C1$ should be charged so far after about 110 milliseconds that tube $B2$ ignites. Signalling relay LA operates on ignition of tube $B2$.

5 In Fig. 1 the time which the signalling relay LA takes to operate is to a high degree independent of the value of battery voltage as long as both battery halves vary in the same manner. The circuits of Figs. 2 and 3 are, however, not independent of voltage fluctuations of tubes if these tubes have a grid swing which is not small compared to battery voltage.

10 It is remarked that if the signalling device is connected to the armature to be supervised with the application of an auxiliary relay cell $S1$ is not required and may be replaced by resistance $W1$ of Fig. 4. The cathode of tube $B1$ is connected to a top of a potentiometer $W4$, $W5$ whereby a certain degree of independence of 15 voltage fluctuations of both battery halves is obtained.

20 While I have illustrated and described what I regard to be the preferred embodiment of my invention, nevertheless it will be understood that 25 this is merely shown by way of example and that numerous modifications and rearrangements may be made therein without departing from the essence of the invention.

I claim:

30 1. A telegraph receiving system comprising a local source of D. C.; a receiving line relay; an armature controlled by said relay so as to alternate between opposite polarities of said D. C. source; a condenser having one terminal connected to one pole of said D. C. source; a resistance having terminals connected, respectively, to said armature and to the other terminal of said condenser; a rectifier connected across said resistance between said armature and the 35 other terminal of said condenser so as to become conductive on said armature making contact with said terminal of said D. C. source connected to said condenser; and signalling means being responsive to the voltage of said condenser 40 surpassing a predetermined limit.

2. A telegraph receiving system comprising a local source of D. C.; a receiving line relay; an armature controlled by said relay so as to alternate between opposite polarities of said D. C. 50 source; a condenser having one terminal connected to one pole of said D. C. source; a resistance having terminals connected, respectively, to said armature and to the other terminal of said condenser; a rectifier connected across said 55 resistance between said armature and the other terminal of said condenser so as to become conductive on said armature making contact with said terminal of said D. C. source connected to said condenser; and signalling means being responsive to the voltage of said condenser surpassing a predetermined limit, and including a tube having a cathode, a grid, and an anode; a resistance connecting said grid with that terminal of said condenser which is connected to said armature, and a signalling line connected to said anode.

3. A telegraph receiving system comprising a local source of D. C.; a receiving line relay; an armature controlled by said relay so as to alternate between opposite polarities of said D. C. 70 source; a condenser having one terminal connected to one pole of said D. C. source; a resistance having terminals connected, respectively, to said armature and to the other terminal of 75 said condenser; a rectifier connected across said

resistance between said armature and the other terminal of said condenser so as to become conductive on said armature making contact with said terminal of said D. C. source connected to said condenser; and signalling means being responsive to the voltage of said condenser surpassing a predetermined limit, and including a tube having a cathode, a grid, and an anode, a resistance connecting said grid with that terminal of said condenser which is connected to said armature, and a signalling line connected to said anode.

4. A telegraph receiving system as claimed in claim 3 including means for biasing said grid of said tube to the predetermined limit.

5. A telegraph receiving system as claimed in claim 3 including an additional rectifier for biasing said grid of said tube to the predetermined limit.
